UNITED STATES PATENT OFFICE.

CHARLES J. VAN DE POELE, OF CHICAGO, ILLINOIS.

DYNAMO-ELECTRIC MACHINE.

SPECIFICATION forming part of Letters Patent No. 247,278, dated September 20, 1881.]

Application filed May 25, 1881. (No model.)

To all whom it may concern:

Be it known that I, CHARLES J. VAN DE POELE, of Chicago, in the county of Cook and State of Illinois, have invented an Improvement 5 in Dynamo-Electric Machines, of which the following is a specification.

My invention relates to new and useful improvements in the construction of electric generators, whereby a large number of independent 10 currents of an alternating character may be produced.

The invention consists in the peculiar construction of parts and their combinations, as more fully hereinafter described.

15 Figure 1 is a side elevation of my improved machine complete and ready for operation. Fig. 2 is a vertical central longitudinal section. Fig. 3 is a rear-end view, showing commutator-ring and insulated brush and holder to send 20 current through electro-magnet in case a second or separate dynamo-machine is employed to saturate said magnets. Fig. 4 is a front-end view, showing coils, brushes and holders, and commutator, by means of which the necessary 25 currents are collected to keep up magnetism in large magnets, making the machine self-contained—that is, not requiring a separate dynamo to keep up the currents in the revolving magnets. Fig. 5 is a cross-section, showing in- 30 ducing-magnets, induced coils, ring to which the induced coils are secured, and the hub carrying the large electro-magnets, of which the hub forms a part.

35 In the accompanying drawings, which form a part of this specification, A A' and B B' represent the four large inducing-magnets, each being secured to the hub H, which is secured upon a shaft, I, journaled in suitable bearings, J, at each end, and driven by a belt upon the 40 pulley K.

45 C represents the armature-plates, around which are wound the wire-coils C'. These plates, carrying said coils, are secured to the rings D by means of screws a, as shown, so that the rings, with an even number of armature-coils—say two or any multiple of two—will form a circular chamber, within which the shaft carrying the magnets may revolve.

50 E are circular plates, of wood or other non-conducting substance, secured to the end of

the armatures, covering the coils thereof, and carrying binding-posts L for the induced coils. There are two of these binding-posts for each one of the armature-coils.

M is the commutator.

N' N'' are brush-holders and brushes, and in Fig. 4 the wire-connections are shown between two opposite coils of the armature and the brush-holders.

O represents a commutator-ring, and O'' an 60 insulated brush-holder and brush, upon the rear end of the machine, designed to be employed in sending currents through the electro-magnets in case a second or separate dynamo is used to saturate said magnets.

65 In practice it is well known that a large field-magnet having once been magnetized will retain a small portion of what is called "remnant magnetism." Now, on revolving said magnets in front of along the sides of the cores and coils of 70 the armature, weak currents will be developed in said coils, but in alternate directions. By properly connecting said coils to the brush-holders and brushes N' N'', as shown in Fig. 4, said currents are made to run in one direction, as 75 all the coils of the magnets are connected with the commutator M, one terminal with one half of the commutator and the other terminal with the other half of said commutator. The currents thus being sent in one direction through 80 the large magnets, their power will be increased and act more powerfully on the coils of the armature. These, in their turn, will send currents of corresponding strength into the large magnets, and so on, keeping up the required mag- 85 netism in said field-magnets as long as the machine is in operation. This explains how the apparatus is made to be self-sustained, requiring no special or separate source of electricity to saturate the revolving field.

90 It will be very easily understood that in all the independent coils currents of alternate directions will be generated as long as the field is revolving in connection with said coils C' C'', Fig. 4, and that many combinations can be 95 made with induced coils and currents, furnishing currents of more or less power, as required.

100 On an examination it will be found that this machine is to a certain extent an inverse construction of the dynamo-machine as patented

to me on September 21, 1880, in patent numbered 232,574. The armature in said patented machine revolves, and the field is stationary, whereas in the present construction I revolve the field within the armature, which is stationary.

The machine herein described, in addition to keeping up its own magnetism, is capable of giving off a large number of independent circuits to be used for lighting or for other purposes. By making the revolving field so as to present only one positive (north) and one negative (south) pole I obtain one very powerful magnet, and, as it takes rather a long time to 15 saturate any other electro-magnet in the vicinity of an inducing-magnet, by this system I give the induced coils the same time to acquire their saturation as in the case of the stationary field. This is not the case, however, where 20 the inducing-magnets are numerous and small. Another advantage I gain, since the apparatus is self-contained, is that the commutator can be made in the simplest of the known forms.

What I claim as my invention is—

25 1. In a dynamo-electric machine, and in combination with the rotary field-magnets A A' B B' thereof, the stationary and circular series

of armature-magnets C', each composed of a core, C, wound in the direction of its length and secured to two or more rings, D, surrounding all the magnets, said armature-cores having their narrow edges adjoining each other, substantially as and for the purpose specified. 30

2. In a dynamo-electric machine, the field-magnets A A' B B', each consisting of a long 35 flat core attached radially to the revolving shaft I in the direction of its greatest length, and provided with a curved polar face projecting past the core in all directions, in combination with the stationary armature-magnets C C', 40 both the armature and the field magnets being wound with wire in the direction of their length, substantially as and for the purpose specified.

3. In a dynamo-electric machine, and in combination with the stationary armature-cores C 45 thereof, the circular flanged insulating-rings E and binding-posts L, said rings being constructed to protect the ends of the armature-coils and to sustain the binding-posts of the coils, substantially as set forth.

CHARLES J. VAN DE POELE.
